DEVICE FOR GAUGING THE CUTTING OF
RAFTERS

Erik O. Karlson, Elmont, N. Y.

Application February 18, 1937, Serial No. 126,348

3 Claims. (Cl. 33—97)

This invention has relation to carpenters' implements and comprehends an improved device for facilitating the computation or determination of the lengths and angles of rafter cuts.

5 The invention broadly aims to provide a device of the indicated character by means of which the average carpenter may expeditiously compute and with the aid of the usual steel square mark the lumber for the various cuts to be made in 10 fashioning common rafters, hip and valley rafters, and jack rafters.

More particularly the invention resides in a 15 device of the character set forth and for the purpose specified which includes a base having graduations, lines and indicia on one surface thereof and cooperative graduated sliding and swinging members adjustable to positions coinciding with the building and roof measurements to compute and determine the lengths of the 20 various rafters and the heel, plumb and angle cuts to be made.

Other objects of the invention reside in the provision of a device of this character which is comparatively simple in its construction and mode of use, inexpensive to produce, highly efficient in its purpose and which is small and compact whereby it may be readily carried in the 25 carpenter's kit or pocket.

With the above enumerated and other objects in view, reference is now made to the following 30 specification and accompanying drawing in which there is disclosed a preferred embodiment of the invention, while the appended claims cover variations and modifications thereof which fall 35 within the scope of the invention.

In the drawing:

Fig. 1 is a face view of the device constructed in accordance with the invention, illustrating the slide member and pivoted arm in adjusted set 40 position.

Fig. 2 is an end edge view thereof as viewed from the left hand edge of the device.

Fig. 3 is a face view illustrating the slide member and pivoted arm in folded inactive compact 45 position for storage of the device.

Fig. 4 is a vertical sectional view taken approximately on the line 4—4 of Fig. 3.

Referring to the drawing by characters of reference, 10 designates the base of the device which 50 is preferably of rectangular configuration having parallel opposite longitudinal side edges 11 and 12 and a plane upper surface 13 which is provided with a longitudinally extending line 14 adjacent to and parallel with the side edge 12 and adjacent one end edge with a perpendicular

transverse line 15. The line 14 is subdivided by longitudinally spaced graduations 16 having associated indicia 17 beginning at the line 15.

A pair of longitudinally extending lines 18 and 19 are also inscribed on the upper surface 13 and said lines are parallel to each other and to the line 14. The line 18 has associated therewith indicia 20 which is here designated "common rafter", while the line 19 has associated therewith indicia 21, here designated "hip or valley rafter". The line 14 together with its graduations 16 and indicia 17 has further indicia 22 associated therewith designated the "rise".

A slide member designated generally by the reference character 23 is mounted for guided sliding movement with reference to the base 10 and said member 23 is preferably of T-shaped construction having a longitudinally extending head 24 which is formed with a groove 25 in its inner edge to slidably fit over the side edge 12 of the base. The slide member 23 further includes a slotted arm 26 disposed at an angle to the head 24 and extending transversely of the base 10 with the base received by the slotted portion so that the arm 26 straddles the same, and the upper surface of the portion of the arm 26 which overlies the base is provided with a series of graduations 27 which start at the line 14 and extend throughout its length to the free end thereof. Indicia 28 is associated with the graduations and the arm 26 is also provided with indicia 29 designated the "run". In order to lock the slide member 23 in adjusted relation to the base, a set screw 30 having a knurled manipulating head 31 is threaded through the outer end edge of the slide arm 26 and is designed to be impinged against the side edge 11 of the base.

The device further includes a swinging arm 32 which is mounted to swing on a pivot 33 having a vertical axis located at the intersection of the lines 14 and 15 adjacent one corner of the base, the edge 34 of the swinging arm intersecting the axis of the pivotal connection of the arm and said edge being provided with a line of graduations 35 and associated indicia 36 starting at the pivotal point of the arm.

The arm is disposed between the resilient furcations of a bracket 37 and the arm is secured in adjusted angular position by means of a thumb nut 38 which threadedly engages the pivot 33 for frictionally clamping the arm between the furcations. In order to limit the swinging of the arm 32 to a position parallel with the head 24 of the slide member, a clip 39 is provided on the head 24 of the slide member.

The upper plane surface 13 of the base is provided with curved lines 40 and 41 which extend from the axis of the pivot 33, diverge with reference to each other and terminate at the opposite 5 end edge of the base. These curved lines are respectively designated by the indicia 42 and 43 as "bevel for hip or valley rafter" and "bevel for jack rafter".

In use and operation, when it is desired to determine the length of a common rafter and the angle of the heel and plumb cuts thereof, the slide is first moved so that the graduated edge of the slide arm coincides with the graduation 16 and indicia 17 corresponding to the rise of the 10 roof. The set screw 30 is then tightened to retain the adjustment and the swinging arm 32 is then swung to a position where its graduated edge coincides with the graduation 27 and indicia 28 which corresponds to the "run" which is half the 15 width of the building. The graduation 35 and indicia 36 on the swinging arm 32 at the point of intersection of the graduated edges of the arms 26 and 32 will give the length of the rafter. By 20 use of the usual carpenter's steel square, the angles of the heel and plumb cuts and the bevel cuts for roofs of equal pitch are obtained as follows: Assuming that the run is "fifteen" feet and the rise "fourteen" feet, first set the slide member at the base graduation 16 indicated by the 25 indicia 17 as "fourteen", then tighten the set screw 30. The swinging arm 32 is then adjusted at an angle where its edge 34 intersects the graduated edge of the arm portion 26 of the slide member 23 at the graduation 27 which corresponds to the run, namely "fifteen" feet. The 30 graduation 35 indicated by the indicia 36 on the swinging arm 32 will indicate the length of the common rafters, namely "twenty feet, six and one-half" inches. For the purpose of obtaining 35 the heel and plumb cuts so that the graduation marked twelve on the blade of the steel square may be used as one measurement, tighten the clamping nut 38 to retain the swinging arm in set position and move the slide until the graduated edge thereof coincides with the intersection 40 of the graduated edge 34 with the common rafter line 18 and tighten the set screw 30. The swinging arm 32 is now released and swung to the out-of-the-way position illustrated in Fig. 3 of the 45 drawing and the base graduation where the slide member arm 26 is now adjusted will give the other reading as "eleven and one-quarter" inches for the steel square tongue. When the steel square is placed on the lumber with the "twelve" inch 50 blade graduation at one edge of the lumber and the "eleven and one-quarter" inch tongue graduation at the edge of the lumber, the marking of the lumber along the edge of the blade will give the heel cut while the marking of the lumber 55 along the edge of the tongue will give the plumb cut.

To determine the heel and plumb cuts for the valley rafter, read the graduation at the point of intersection of the hip or valley rafter line designated 19, with the slide arm 26, and the reading for the steel square will then be "eleven and one-quarter" inches on the tongue and "seventeen" inches on the blade, the latter being the reading shown at the hip and valley rafter line. 60 To determine the setting of the steel square for the bevel cut of a hip or valley rafter, read the graduation on the slide arm 26 at the intersection with the curved line designated "bevel for hip or valley rafter" which, in the example 65 given, will be found to be "nine and three-

eighths" inches which combined with the base graduation at the intersection of the slide arm 26, is "eleven and one-quarter" inches. The steel square is then laid on the edge of the lumber and marked along the tongue of the steel 70 square.

The plumb cuts at the opposite ends of the jack rafters are the same as the plumb cuts for the common rafter and the bevel of the lower plumb cut which is to rest against the side of the valley 75 rafter is obtained by reading the base graduation which shows "eleven and one-quarter" inches and the slide graduation at the intersection of the curved line marked "bevel for jack rafter" which is found to be "eight and one-quarter" inches. 15

In order to determine the length of the valley rafter, adjust the swinging arm 32 to the point of intersection of the graduated edge of the slide arm with the line 19 designated "hip or valley rafter" and tighten the clamping nut 38. Then move the slide to the base graduation 16 which corresponds to the rise of "fourteen" feet and read the graduation 35 on the swinging arm 32 at the point of intersection of the graduated edge of the slide arm 26 with the swinging arm 32. 20 This, in the example being given, will show "twenty-five feet, six inches". 25

To determine the difference in length between the common rafter and the first jack rafter, move the slide arm 26 to the base graduation "eleven and one-half", set the swinging arm 32 to the point of intersection of the line 41, designated "bevel for jack rafter", tighten the swinging arm in this position and then move the slide arm 26 to the point where it intersects the edge 34 of the swinging arm 32 at the graduation 27 on the slide arm which corresponds to the spacing of the jack rafters, which spacing has been predetermined, say for example, as "sixteen" inches apart. By then reading the graduation 16 and indicia 17 on the base at the intersection of the graduated edge of the slide arm, the difference in length between the common rafter and the first jack rafter, as well as between each of the 30 succeeding jack rafters, will be obtained in inches 35 and will in the example given be "twenty-one and seven-eighths" inches. 40

What is claimed is:

1. In a device for computing rafter cuts, a base having a plane upper surface, a slide member overlying and extending across the upper surface of the base, means mounting the slide member for guided sliding movement lengthwise of the base, an arm pivoted adjacent one corner of the base, means for locking the slide member and arm respectively in adjusted relation to each other, and curved lines on the surface of the base extending from the pivotal point of the arm for obtaining readings to determine the angle of the bevel cuts for the hip or valley and jack rafters. 50

2. In a device for computing rafter cuts, a rectangular base having a surface inscribed with lines and indicia, a T-shaped slide member having a slotted arm portion straddling and extending across opposite surfaces of said base, graduations and indicia on the surface of the arm portion overlying the inscribed surface of the base, a slotted head portion of said slide member engaging over one edge of the base for mounting the slide member for guided sliding movement lengthwise of the base, an arm pivoted adjacent one corner of the base having graduations and indicia thereon, and means for locking the slide member and arm respectively in adjusted relation to each other, the lines on the surface of the base 55

being so arranged as to be intersected by the slide member and the pivoted arm for designating the points of reading of the graduations to determine the length of common, hip and valley rafters and the angles of the cuts to be made.

5. 3. A device for computing rafter cuts including a base having a plane surface bearing a lengthwise line having graduations for indicating the rise, a pair of parallel lines spaced therefrom and from each other for use in computing the cuts of common rafters and hip or valley rafters respectively, and divergent curved lines for use in 10 computing the bevel cuts of the jack rafters and hip or valley rafters respectively, a slide member

overlying the surface of said base extending thereacross perpendicular to the parallel lines, mounted for guided sliding movement lengthwise thereof and having graduations indicating the run and cooperating with said parallel and curved lines to compute said rafter cuts, a graduated arm pivoted to said base at the intersection of the curved lines with each other and with the graduated line indicating the rise for the purpose of computing the length of the rafters, and 15 means for locking the slide member and arm respectively in adjusted positions.

ERIK O. KARLSON.
